UNITED STATES PATENT OFFICE.

ALFRED C. GREENE, OF SOUTHPORT, ENGLAND.

CHAIR.

SPECIFICATION forming part of Letters Patent No. 655,224, dated August 7, 1900.

Application filed December 18, 1899. Serial No. 740,752. (No model.)

To all whom it may concern:

Be it known that I, ALFRED CHARLES GREENE, a subject of the Queen of Great Britain, residing in Southport, in the county of 5 Lancaster, England, (whose post-office address is 62 Belmont street, Southport, aforesaid,) have invented certain new and useful Improvements in Chairs, (for which application has been made in England, No. 16,815, 10 dated August 18, 1899,) of which the following is a specification.

This invention has for its object to provide a folding or other chair, stool, or the like in which the canvas or other material forming 15 the seat is detachable from the frame. Hitherto in many cases the canvas or other suitable material has been permanently fixed to the chair or stool, so that it could not be taken off without great difficulty and when removed 20 could not readily be replaced again.

Referring to the accompanying drawings, Figure 1 is a perspective view of so much of a chair or similar piece of furniture as is necessary to illustrate one embodiment of my invention; Fig. 2, a detail view thereof; Fig. 3, a further detail; Fig. 4, an elevation of a modified form; Fig. 5, a cross-section, and Fig. 6 a perspective view, of said modified form.

The material A, forming the seat, and which 30 will be herein referred to as "canvas," is provided with round eyelets J, let into the ends of the canvas. These eyelets slip over hooks K, fixed underneath the rails B of the chair. To make the attachment more secure, a rod 35 k, preferably of metal, is passed through holes L in the sides of the chair I and through each of the hooks K, or against the pegs, if such are used instead of the hooks K. Metal disks M, Fig. 3, are provided to cover the 40 holes L after the rod k is in place, thereby preventing said rod from slipping out.

Instead of having holes cut in the sides I of the chair brackets or catches may be fixed to the sides thereof, which would lock the rod 45 in position.

The arrangement shown in Figs. 4, 5, and 6 is somewhat similar except that the rod G rests against a curved metal strip N, fixed underneath the cross rail or bar B of the chair, and one of its ends fits into a socket O, 50 its other end being held by a sleeve P, which screws onto a stud Q, fixed to the frame of the chair. Obviously if the screw P be unscrewed from the stud it will free the rod G, which can then be withdrawn from the socket 55 O. The end of the cloth or canvas with this construction is clamped between the metal strip N and the cross-bar B, and being brought around, as shown in Fig. 6, over the upper face of said cross-bar B it does not slip. 60

Having thus described my invention, what I claim is—

1. The combination with a chair having cross-rungs and a fabric engaging said rungs, of eyelets J let into the ends of the fabric; 65 hooks K fixed to the cross-rungs; and a rod adapted to pass through the hooks, substantially as described.

2. The combination with a chair having cross-rungs and a fabric engaging said rungs, 70 of eyelets J let into the ends of the fabric; hooks K fixed to the cross-rungs; a rod G adapted to pass through the hooks and through the side bars of the chair; and means for preventing endwise movement of the rod. 75

3. In a chair, the combination of the side bars or members I; a rung B extending across between the same; means carried by said rung for engaging the chair fabric; and a bar secured beneath said rung B, adapted 80 and arranged to act in conjunction with said means carried by the rungs.

In witness whereof I have hereunto signed my name, this 29th day of November, 1899, in the presence of two subscribing witnesses. 85

ALF. C. GREENE.

Witnesses:

G. C. DYMOND,
W. H. BEESTON.
